(57) **CLAIM**

The ornamental design for a cooking indentation, as shown and described.

DESCRIPTION

FIG. 1 is a top plan view of the cooking indentation with the broken lines in the drawing illustrating a cooking tray in which multiple cooking indentations are embodied, the broken lines not being a part of the design sought to be patented.

FIG. 2 is a top perspective view of the cooking indentation with the break lines illustrating connection into the cooking tray which is not a part of the design sought to be patented. FIG. 3 is a bottom perspective view of the cooking indentation.

FIG. 4 is a top view of the cooking indentation.

FIG. 5 is a bottom view of the cooking indentation; and, FIG. 6 is a side elevation view of the cooking indentation. All side views of the cooking indentation are identical to FIG. 6.
